(57) **CLAIM**

The ornamental design for a propeller display as shown and described.

DESCRIPTION

FIG. 1 is a front perspective view of a propeller display showing my new design;

FIG. 2 is a front elevation view thereof;

FIG. 3 is a rear elevation view thereof; and,

FIG. 4 is a top view thereof.

The stippling in the drawing disclosure represents a contrast in appearance.

The portions of the propeller display shown in broken lines forms no part of the claimed design.
